UNITED STATES PATENT OFFICE.

GEORGE J. HAGAN, OF PERRYSVILLE, PENNSYLVANIA, ASSIGNOR TO GEORGE J. HAGAN COMPANY, OF PITTSBURGH, PENNSYLVANIA, A CORPORATION OF PENNSYLVANIA.

BAR AND SHEET HEATING FURNACE.

Application filed April 17, 1923. Serial No. 632,753.

To all whom it may concern:

Be it known that I, GEORGE J. HAGAN, residing at Perrysville, in the county of Allegheny and State of Pennsylvania, a citizen of the United States, have invented or discovered certain new and useful Improvements in Bar and Sheet Heating Furnaces, of which improvements the following is a specification.

10 In an application filed of even date herewith (Case A) a construction of furnace is claimed having independent or separate portions adapted respectively for heating sheet bars and sheets combined with a combustion chamber from which the products of combustion pass successively through the heating portions of the furnace on their way to the stack, said application also including as a preferential embodiment of the invention, a construction wherein the products of combustion flow from the combustion chamber through the sheet heating chamber into the bar heating portion and thence to the stack.

25 The invention described herein has for its object a construction having independent sheet and bar heating portions and wherein the products of combustion flow first through the bar heating portion to the sheet heating portion and thence to the stack. It is a further object of the invention to provide a combustion chamber for each of two bar heating chambers both of which are connected to the sheet heating chamber and the latter connected to a stack. The invention is hereinafter more fully described and claimed.

30 In the accompanying drawings forming a part of this specification, Figure 1 is a sectional plan view of a furnace embodying the improvements claimed herein;

Figure 2 is a sectional view on a plane indicated by the line II—II, Figure 1; and

45 Figures 3 and 4 are views similar to Figures 1 and 2 illustrating a modification of the construction shown in Figures 1 and 2.

The furnace in the construction shown in Figures 1 and 2 is provided with a bar heating chamber 1 and a sheet heating chamber 2, the bar heating chamber extending along one side of the sheet heating chamber and projecting at its rear end beyond the sheet heating chamber. The bar heating chamber is provided at its rear end with

50 means 3 for feeding bars into and forcing

them through the bar heating chamber and at its opposite end with a suitable door 4. The front end of the sheet heating chamber is also provided with door 5 for charging and discharging sheets in packs or in singles. 60 In the rear of the sheet chamber and at one side of the extended end of the bar heating chamber is arranged a combustion chamber 6 which is connected by a port 7 with the bar heating chamber, said port being 65 adjacent to the rear or charging end of said chamber. The front ends of the bar and sheet heating chambers are connected by a flue or passage 8 and in the rear wall 9 of the sheet heating chamber are formed flues 70 10 connected at their lower ends with sheet heating chamber and at their upper ends with the stack. The flow of products of combustion from the bar heating chamber to the sheet heating chamber is controlled 75 by a suitable damper which in the present case consists of a movable tile 11 adapted to regulate the flow of products of combustion through the ports 8.

80 In the construction shown in Figures 3 and 4 a bar heating chamber 1^a is arranged on each side of the sheet heating chamber 2 and the bar heating chambers are extended rearwardly beyond the end of the sheet heating chamber. It is preferred to employ two 85 combustion chambers 6^a, which in the construction shown are arranged in the rear of the sheet heating chamber and intermediate the extended portions of the bar heating chambers. These combustion chambers 90 are connected respectively by port 7^a to the bar heating chambers at points adjacent to the rear or charging ends of said chambers. The bar heating chambers are connected at or near their front ends to the sheet heating 95 chamber by ports or passages 8^a and suitable dampers 11 are employed for controlling the flow of products of combustion from the bar heating chambers to the sheet heating chamber. The sheet heating chamber is 100 connected, as hereinbefore described, to the stack by flues or passages 10 formed in the rear wall of the sheet heating chamber. In this construction, provision is made for heating the bar heating chambers by products of combustion independently derived from independent combustion chambers in the rear of the sheet heating chamber.

105 As is well known, it requires a larger number of thermal units to heat the sheet bars 110

which have comparatively small superficial area than is required to heat the sheets which have quite a large area and the construction shown herein provides for conditions when the temperature of the gaseous fuel passing through one bar heating chamber is not sufficiently high to properly heat the sheets.

It will be understood that although means for the combustion of gaseous or liquid fuel is shown in the drawings, any other kind of fuel may be employed in the combustion chamber.

I claim herein as my invention:

1. A furnace having in combination a sheet heating chamber, a bar heating chamber, said chambers being connected adjacent to their front ends, a combustion chamber connected to the bar heating chamber at a point adjacent to its rear end and a stack connected to the sheet heating chamber adjacent to its rear end.

2. A furnace having in combination a sheet heating chamber, bar heating chambers ex-

tending along opposite sides of the sheet heating chamber and connected to the latter adjacent to its front end, two combustion chambers arranged in the rear of the sheet heating chamber and connected respectively to the bar heating chambers at points adjacent to the rear ends thereof, and a stack connected to the sheet heating chamber adjacent to the rear end of the latter.

3. A furnace having in combination a sheet heating chamber, bar heating chambers connected to the sheet heating chamber at points adjacent to the front end of the latter, means for supplying heat to the bar heating chambers at points adjacent to the rear ends of the latter, a stack connected to the sheet heating chamber at a point adjacent to the rear end of the latter, and dampers for controlling the flow of products of combustion from the bar heating chambers to the sheet heating chamber.

In testimony whereof, I have hereunto set my hand.

GEORGE J. HAGAN.
